UNITED STATES PATENT OFFICE.

MARION C. WALLS, OF CLAYTON, INDIANA.

PUMP.

Specification of Letters Patent. Patented Jan. 15, 1918.

1,253,914.

Application filed November 28, 1916. Serial No. 133,908.

To all whom it may concern:

Be it known that I, MARION C. WALLS, a citizen of the United States, residing at Clayton, in the county of Hendricks and State of Indiana, have invented new and useful Improvements in Pumps, of which the following is a specification.

This invention relates to pneumatic pumps and it consists in novel features hereinafter described and claimed.

An object of the invention is to provide a pump of the character stated and which is automatic in its action and having its parts so arranged as to lift water successively from a plurality of cylinders whereby the water is caused to flow from the discharge pipe of the pump in a continuous stream notwithstanding the fact that the air is admitted alternately to these cylinders and hence one cylinder is inactive while the other cylinder is in active operation.

With these objects in view the structure comprises an inner and an outer cylinder adapted to be submerged in the water of a well or similar container there being valve controlled ports leading into both of the cylinders. The water pipe leads from the said cylinders and is provided with branches which enter the cylinders and terminate at their lower ends in the vicinity of the lower ends thereof. Air pipes lead into the upper ends of the cylinders and means are provided at the top of the well for controlling the passage of air through the said air pipe whereby the air is caused to pass through the pipes alternately or at different intervals of time.

In the accompanying drawings:

Figure 1 is a side view of the pump with parts broken away.

Fig. 2 is a fragmentary front view of the upper portion of the same with parts shown in section.

Fig. 3 is a vertical sectional view through the cylinders of the pump.

Fig. 4 is a detailed view of parts of the pump showing some of the illustrated parts in section.

Fig. 5 is a horizontal sectional view through the cylinders of the pump cut on the line 5-5 of Fig. 3.

Fig. 6 is a transverse sectional view of the upper portion of the pump.

Fig. 7 is a detailed view of parts of the pump showing some of the illustrated parts in section.

Fig. 8 is a detailed sectional view of parts of the pump.

The pump comprises a cylinder 1 which is adapted to be immersed in the water of a well below the surface thereof. A fitting 2 is attached to the lower end of the cylinder 1 and is provided with a port 3. A valve 4 is hingedly mounted in the fitting 2 and normally rests by gravity over the port 3 and closes the same. An air pipe 5 leads into the upper end of the cylinder 1. A pipe 6 passes transversely through the lower portion of the cylinder 1 and carries a fitting 7 which communicates with the interior of the said pipe 6 to a port 8. A valve 9 is hingedly mounted in the fitting 7 and normally lies by gravity over the port 8 and closes the same. An air pipe 10 leads into the upper end of a cylinder 11 which is mounted upon the fitting 7 and traverses the length of the upper portion of the cylinder 1. The main or body portion of the cylinder 11 is inclosed within the cylinder 1 as best shown in Fig. 3 of the drawing.

A water pipe 12 is provided at its lower end with branches 13 which enter the cylinders 1 and 11 respectively and terminate at their lower ends in the vicinity of valves 4 and 9. The said branches 13 are provided with check valves 14 of conventional pattern. A casing 15 is adapted to be positioned at the top of the well and a tank 16 is supported therein by means of rods 17. As shown in Fig. 7 a branch pipe 18 connects at one end with the pipe 12 and at its other end with a valve casing 19. A pipe 20 connects at one end with the pipe 12 and at its other end with the side of the casing 19. The pipe 21 connects at one end with the casing 19 at a point opposite the point of connection between the pipe 20 and the said casing and the other end of the said pipe 21 leads into the upper portion of the tank 16 as best shown in Fig. 6.

A valve 22 is slidably mounted in the casing 19 and is provided with a port 23 which at times is brought into register with the ends of the pipes 20 and 21. A spring 24 is housed in the casing 19 and bears at one end against the end of the same and at its other end against the valve 22 and is under tension with a tendency to hold the valve toward the adjacent end of the pipe 18.

When water is flowing through the pipe 12 the spring 24 holds the valve 22 in position against the end of the pipe 18 whereby

the port 23 is brought into register with the pipes 20 and 21, consequently water may pass from the pipe 12 through the pipes 20 and 21 and flow into the tank 16. As soon as the flow of water is stopped through the pipe 12 the back pressure of the water in the said pipe is such as to cause the water in the pipe 18 to move longitudinally thereof whereby the valve 22 is moved back against the tension of the spring 24 and the port 23 is moved out of register with the ends of the pipes 20 and 21. Thus the solid portion of the valve 22 is interposed between the adjacent ends of the pipes 20 and 21 and communication through the said pipes is interrupted, thus the flow of the water from the pipe 12 into the tank 16 is automatically checked or stopped when the flow of water through the pipe 12 is interrupted and the water which remains in the said pipe is subjected to pressure. The pipes 20 and 21 afford means for supplying water to the tank 16 when the water is flowing through the pipe 12 and the pipe 18 together with the valve 22 serve as means for interrupting the flow of water from the pipe 12 to the tank 16 when the flow of water through the pipe 12 is stopped.

Pipes 25 depend from the bottom of the tank 16 and are provided with valves 26 of usual pattern. Clips 27 are attached to the lower portion of the pipes 25 and levers 28 are fulcrumed upon the said clips. The said levers 28 carry valves 29 located at one end and adapted to close against the lower ends of the pipes 25 and the said levers 28 carry at their other ends weights 30. The said weights 30 normally hold the valves 29 in closed position against the lower ends of the pipes 25.

A shaft 31 is mounted below the tank 16 and a bar 32 is mounted upon the said shaft for turning movement about the axis thereof. The said bar 32 carries at its ends outstanding pins 33 and the inner weighted ends of the levers 28 are located in the paths of movement of the said pins. An arm 34 is fixed to the shaft 31 and the bail handles of buckets 35 are pivotally connected with the ends of the said arms 34. The pins 33, hereinbefore described, extend transversely across the paths of movement of the end portions of the arms 34. The buckets 35 are mounted at their bottoms with nipples 36 and valves 37 normally rest upon the upper ends of the said nipples and close the same. The stems 38 pass through the nipples 36 and project below the lower ends thereof. Disks 39 are mounted upon the intermediate portions of the stems 38 and are normally spaced from the lower ends of the nipples 36.

The bottom of the casing 15 is provided with openings 40, best shown in Fig. 2, through which the lower portions of the

stems 38 may pass when the buckets descend to their lower positions and consequently as each bucket approaches the bottom of the casing 15, the disk 39 attached to that bucket may come in contact with the bottom of the casing whereby the valve stem 38 is moved longitudinally in the nipple 36 and the valve 37 is moved to an open position as shown at the left in Fig. 2. Therefore any water which has been poured into the bucket 35 may escape through the nipple and flow through the opening 40 out of the casing 15.

When the bucket 35 is at its lower position as shown at the left in Fig. 2 the valve 29 above the said bucket is in closed position against the lower end of the pipe 25 above the said bucket, but it will be observed that the pins 33 at the right hand end of the bar 32 is in contact with the longer end of the lever 28 at the right of the said figure consequently the valve 29 is in an open position below the pipe 25 and the water may flow from the tank 16 through the pipe 25 at the right of the said tank and enter the bucket 35 below. A weight 41 is mounted upon the intermediate portion of the arm 34 and is adapted to swing transversely across a plane passing vertically through the axis of the shaft 31 as the said arm 34 swings. When a quantity of water has been accumulated in the bucket 35 at the right sufficient to overcome the weight 41 the bucket 35 at the right descends and the bucket 35 at the left ascends. This causes the arm 34 to swing whereby the weight 41 is carried from one side of the vertical plane passing through the axis of the shaft 31 to the opposite side of the said plane. As the left hand end of the arm 34 moves in an upward direction it encounters the pin 33 just above the same and the bar 32 is swung whereby the pin at the right hand end of the said bar is moved below the weighted end of the lever 28 at the right hand side of the figure and the valve 29 at the right hand side of the figure assumes the closed position at the lower end of the pipe 25 just above. When the pin 33 at the left hand of the bar 32 strikes the lever 28 at the left of the said figure the said lever is swung whereby the valve 29 carried by the same is moved from under the lower end of the pipe 25 and therefore the water may flow from the tank 16 into the bucket 25 which is located at the left of the figure. Therefore it will be seen that the water which is introduced into the tank 16 is used as a means for turning the shaft 31 alternately in opposite directions.

An air inlet pipe 42 passes vertically through the tank 16 and an air exhaust pipe 43 also passes in a similar manner through the said tank. The pipe 43 is provided at a point below the bottom of the tank 16 with a seat 44 and a valve 45 is located in the lower portion of the pipe 43 and is adapted

to engage at its upper end the seat 44 when the parts are in positions as shown in Fig. 4 of the drawing. The upper end of the pipe 5 communicates with the interior of the pipe 43 by means of a branch 46, the said branch 46 joining with the pipe 43 at a point between the ends of the valve 45. The lower portion of the valve 45 projects below the lower end of the pipe 43 and is provided 10 with a loop 47. The upper end of the pipe 10 communicates with the interior of the pipe 43 through the sides thereof and the valve 45 is provided with a port 48 adapted to be brought into register with the upper end of the pipe 10 when the valve 45 is in its elevated position in the pipe 43.

A casing 49 is mounted at the lower end of the pipe 42 and communicates with the same through ports 50 and 51. A pipe 52 is 20 connected at one end with the casing 49 at a point opposite the port 50 and the said pipe 52 at its other end is connected with the upper end of the pipe 5. A pipe 53 is connected at one end with the casing 49 at a 25 point opposite the port 51 and at its other end with the upper portion of the pipe 10. A valve 54 is slidably mounted in the casing 49 and is provided at its lower end with an eye or loop 55. The said valve 54 is further 30 provided with ports 56 and 57 which are spaced from each other a distance greater than the distance between the ports 50 and 51 hereinbefore described. A bar 58 is fixed to the shaft 31 and passes through the loops 35 47 and 55 as most clearly indicated in Fig. 4 of the drawing.

Assuming that the parts are in position as shown in Fig. 4 of the drawing the operation of the pneumatic features of the de- 40 vice is as follows:—

Compressed air is passed through the inlet pipe 42 and in view of the fact that the port 51 is in register with the port 50 the air passes from the said pipe through the 45 said ports and the pipe 52 into the upper end of the pipe 5. It will be observed that the valve 45 is in a closed position across the end of the branch pipe 46 mounted at the upper end of the pipe 5. The compressed 50 air passes down the pipe 5 and enters the upper end of the cylinder 1. In view of the fact that the said cylinder is submerged below the surface of the water, the water which is in the cylinder is forced in a down- 55 ward direction and up through the branch pipe 13 which enters the cylinder 1 and the pipe 12 and out at the upper end thereof. During this time the port 48 is in register with the upper end of the pipe 10 as shown in Fig. 4 and the air from the cylinder 11 60 may exhaust through the pipe 10 and pass through the port 48. Thus the water may flow through the pipe 6 and the fitting 7 into the cylinder 11. When the cylinder 1 is 65 emptied and the cylinder 11 is filled with

water the shaft 31 is turned as hereinbefore described. Thus the valve 45 is moved away from the seat 44 and the air may exhaust from the cylinder 1 through the pipe 5 and branch 46 and pipe 43. When the said valve 70 45 is lowered in the pipe 43 the port 48 is carried below the upper end of the pipe 10 and consequently the upper end of the said pipe is closed. When the valve 54 is ele- 75 vated in the casing 49 the port 57 is brought 80 into register with the port 51 and the end of the pipe 53 and the port 56 is moved out of register with the port 50 and the end of the pipe 52. Consequently the air may pass from the pipe 42 through the port 51 and 85 port 57 and pipe 53 into the pipe 10 and enter the upper portion of the cylinder 11 and force the water from the said cylinder. The said water passes from the cylinder 11 up through that branch 13 which enters the 90 same and out through the pipe 12.

Therefore it will be seen that the cylinders 1 and 11 are adapted to take in the water at alternate intervals and the air operating upon the water so admitted into the 95 cylinders forces the same from the cylinders at alternate intervals thus the said water passes out through the same pipe in the form of a continuous stream.

Having described the invention what is 95 claimed is:—

1. A pump comprising an inner and an outer cylinder, a pipe passing transversely through the outer cylinder and communicating with the inner cylinder, both of the said 100 cylinders having valve controlled ports, water pipes leading from the cylinders and means for admitting air to the cylinders.

2. A pump comprising a plurality of cylinders, a pipe having branches communicat- 105 ing with the cylinders, a tank located above the cylinders, pressure controlled means for permitting the water to pass from said pipes to the tank, valve controlled outlet pipes connected with the tank, an arm pivotally 110 mounted below the tank, valved buckets carried by the arm and adapted to receive water from the last mentioned pipe, means for admitting air into the cylinders and means adapted to be operated by the said arm for 115 admitting the air into the cylinders successively.

3. A pump comprising a plurality of cylinders, a water pipe having branches communicating with the cylinders, a tank positioned above the cylinders, a pressure controlled means for permitting the water to pass from the pipe into the tank, valve controlled outlet pipes connected with the tank, an arm pivotally connected at a point below 125 the tank and carrying a weight which is adapted to be swung from a point at one side of a vertical plane passing through the pivot of the arm to the opposite side thereof, valved buckets carried by the arm and adapt- 130

ed to receive water from the last mentioned pipe, means for admitting air into the cylinders, means adapted to be operated by the said arm for opening at the water outlet pipe 5 and means adapted to be operated by said arm for admitting the air to the cylinders successively.

4. A pump comprising a plurality of cylinders, a water pipe having branches communicating with the cylinders, a tank positioned above the cylinders, pressure controlled means for permitting the water to flow from the pipe into the tank, water outlet pipes connected with the tank, levers fulcrumed to the said pipes and having valves adapted to close the same and provided with weights, a bar pivotally mounted and having pins adapted to engage the levers, an arm pivoted below the tank and adapted to engage the said pins, valved buckets carried by the arm and adapted to receive water from the outlet pipe and means adapted to be operated by the said arm for admitting the air to the cylinders successively.
5. A pump comprising a plurality of cylinders, a water pipe having branches communicating with the same, a tank located in an elevated position above the cylinders, pressure controlled means for permitting water to pass from the pipe into the tank, water outlet pipes connected to the tank,

valved levers fulcrumed to the pipe and adapted to close the same, an arm pivoted below the tank, valved buckets carried by the arm and adapted to receive the water from the outlet pipe, a bar pivotally mounted and having pins located in the path of movement of the said arms, said pins adapted to engage the levers whereby the valves carried by same are moved away from the outlet pipe, pipes for admitting air into the cylinders, valves controlling said pipes, a bar operatively connected with the said valves and adapted to move the same whereby the air is admitted to cylinders successively.

6. A pump comprising a tank, a pipe passing vertically above the tank, means for forcing water through said pipe, a casing having a pipe connection with the tank, there also being spaced pipe connections between the said casing and the first mentioned pipe, and a spring pressed valve slidably mounted in the casing and having a port adapted to register with the pipe connection with the tank and one of the pipe connections with the first mentioned pipe and adapted to be subjected to water pressure from the first mentioned pipe through the other pipe connection therewith.

In testimony whereof I affix my signature.
MARION C. WALLS.
